UNITED STATES PATENT OFFICE

2,097,576

MACHINE FOR OPERATING ON SHOES

William Thomas Buckingham Roberts, Leicester, England, assignor to United Shoe Machinery Corporation, Paterson, N. J., a corporation of New Jersey

Application June 23, 1936, Serial No. 86,838
In Great Britain August 13, 1935

29 Claims. (Cl. 12—123)

This invention relates to machines for operating on shoes and more particularly to means for positioning or holding shoes in such machines, the term "shoes" being generally used herein to include what are known as boots. The invention is herein illustrated as applied to a toe-lasting machine provided with novel toe-lasting means claimed in a copending application of Frank B. Keall, Serial No. 86,828, filed on June 10, 1936, but it is to be understood that it is not limited to machines of that particular character or to machines for lasting shoes.

In United States Letters Patent No. 1,993,117, granted on March 5, 1935 upon an application of mine, there is disclosed, in a toe-lasting machine, a shoe support or jack having a shoe-positioning member for engaging the bottom of the forepart of a shoe, a toe rest and a heel rest movable respectively heightwise and lengthwise of the shoe 20 to clamp and hold the shoe, and a member movable by the operator to force the toe and heel rests against the shoe, together with means for moving the shoe support and the shoe a predetermined distance toward the toe-lasting means 25 by the movement of that member. In one aspect of the present invention an object is to provide certain improvements in the earlier construction such as to adapt it still better for use in operating on shoes of different sizes and on long-legged 30 boots, and such also as to facilitate its use by the operator. For better accommodation to shoes of different sizes the construction herein shown includes provision for yield in the mechanism movable by the operator to force the toe and heel 35 rests against each shoe, together with means whereby these rests are forced positively against the shoe near the end of the shoe-clamping operation, whatever the size of the shoe. Quickly operable means also is provided for effecting an 40 adjustment of the mechanism to operate on shoes which differ greatly in length.

To facilitate movements of the shoe support toward and from the means which operates on the toe end of the shoe, the support in the construction herein shown is mounted on parallel links, the arrangement being such that the weight of the support tends to swing the links in a direction to carry the shoe away from the operating means. Springs also are provided to assist in initiating the movements of the support in both directions. Still further facility in the use of the shoe support is afforded by a novel construction and arrangement of means for effecting the clamping of the shoe and the movement 55 of the support toward the operating means.

The above and other features of the invention, including also a novel construction such as to avoid interference with the upper of a long-legged boot, novel heel-rest controlling and adjusting mechanism, and various novel details of construction and combinations of parts, will now be more particularly described with reference to the accompanying drawings and thereafter pointed out in the claims.

In the drawings,

Fig. 1 is a view in front elevation of a machine in which the invention is embodied;

Fig. 2 is a plan view of the machine;

Fig. 3 is a front elevation, on a larger scale than Fig. 1, illustrating in greater detail features 15 of the shoe support or jack;

Fig. 4 is a vertical sectional view of certain parts shown in Fig. 3; and

Fig. 5 shows partly in front elevation and partly in section certain other parts shown in Fig. 3. 20

The machine in which the invention is herein illustrated as embodied, like that shown in the above-mentioned copending application, is provided with toe-lasting means comprising a pair of wipers 2 mounted for advancing and closing movements to embrace the toe of a shoe and to wipe the marginal portion of the toe end of the upper materials inwardly over an insole and, in the case of a welt shoe, against a lip on the insole. The wipers 2 are advanced and closed by a hand lever 4 and are thrust still more forcibly against the shoe by fluid-pressure means which it is unnecessary to describe herein for an understanding of the present invention. The wipers also are raised by a double-acting treadle 6, connected to a vertically movable trunk 7 on which they are supported, to wipe the upper heightwise of the toe before wiping its marginal portion inwardly over the insole, and by this treadle they may be forced downward to increase 30 their pressure on the upper in wiping it inwardly all as fully disclosed in the above-mentioned application. 35

To position and hold the shoe for the operation of the wipers thereon there is provided a shoe support or jack so constructed as to receive and hold either riding boots with long legs or shoes with low uppers and which requires but little adjustment to adapt it for shoes of large or small sizes. The jack comprises an insole-engaging plate 8 which occupies a fixed position heightwise of the machine during the lasting operation and against which the toe portion of the insole is placed by the operator in presenting the shoe bottom upward to the machine, a toe rest 10 ar- 50

ranged to be raised to clamp the toe portion of the shoe against the lower face of the plate 8, and a heel rest 12 arranged to be moved into contact with the heel end of the shoe to support the shoe against heelward movement in the lasting operation. The insole-engaging plate, the toe rest and the heel rest are generally similar in their arrangement to corresponding parts shown in the previously mentioned Letters Patent No. 1,993,117.

The insole-engaging plate 8 is a rigid member curved in plan similarly to the toe end of an insole so as to fit closely within and support the lip of a welt shoe insole around the toe portion during the lasting operation and its lower face lies generally in a horizontal plane. The plate is secured in a quickly detachable manner to the left-hand end of a horizontal shank 14 the right-hand end portion of which is secured in a horizontal guideway formed in the upper face of an overhanging arm 16 of a somewhat U-shaped jack casting 18. The central portion of the lower horizontal arm 20 of this casting, in the construction herein shown, is offset rearwardly, as indicated at 22 in Fig. 2, so that the upper of a long-legged boot may hang downwardly at the front of this offset portion without being obstructed by it.

The toe rest 10 (Fig. 3) comprises a rubber pad supported with freedom for rocking movement on the rounded upper ends of lugs 24 extending upwardly at the front and rear portions of a member 26 mounted to swing about an axis extending lengthwise of the shoe in an arcuate guideway 28 formed in the upper end of a lever 30 which is pivotally supported between its upper and lower ends as hereinafter described. This lever is also pivotally supported at its lower end on a pin 32 adjustable by means of a screw 34 along a slot 36 formed in the left-hand end of a short link 38, the screw being threaded in the pin 32 and having thereon a knurled head for turning it. The link 38 is pivoted at its right-hand end on a horizontal pin 40 secured in the left-hand end portion of the lower arm 20 of the jack casting 18. By adjusting the lower end of the lever 30 to the right or the left along the slot 36 and thereby swinging the lever the toe rest 10 may be adjusted in directions lengthwise of a shoe for shoes of different sizes or styles. About midway of its length the lever 30, as above suggested, is pivotally connected by a pin 42 to the left-hand end of a short curved lever arm 44 which is keyed at its right-hand end to the forward end of a rearwardly extending pin 46 rotatable in the lower arm of the jack casting. A second curved lever arm 48 is keyed at its left-hand end to the rear end of the pin 46, and the right-hand end of this arm extends into a slot formed in the lower end portion of a slide 50 which is mounted in upwardly extending guideways 52 formed in the inner sides of the upper portions of an upstanding bifurcated link 54. The arm 48 is pivotally connected to the slide 50 by a pin 56. The upper ends of tension springs 58 are connected to pins 60 projecting from the upper end of the slide 50 and to pins 62 projecting from the link 54 at the lower end of the latter. These springs tend to maintain the slide 50 in a definite lowered position relatively to the link 54 determined by a plate 64 which is fast on the slide and abuts against the upper end of the link, and they also provide yielding means through which downward movement of the link 54 causes the toe rest 10 to be raised by the swinging of the arms 48 and 44.

For imparting downward movement to the link 75 54 its lower end is pivotally connected to the left-

hand end of a substantially horizontal floating lever 66 which near its left-hand end is connected by a pivot pin 68 to the left-hand end of a bifurcated arm 70 of a three-armed lever 72. The lever 72 straddles the upper side of the floating lever 66 and is mounted below this lever on a pair of coaxial pins 74 fixed respectively in the front wall of the rearwardly offset portion of the lower arm of the jack casting and in a web 76 (Fig. 2) parallel to the front wall of the lower arm and spaced from this wall rearwardly of the machine. The two pins 74 are spaced somewhat toward the right from the pin 68 which connects the three-armed lever to the floating lever. A second arm 78 of the three-armed lever is curved upwardly and toward the right and its right-hand end is pivotally connected by a pin to a double link 80 extending downwardly and toward the right. The lower end of the double link 80 is pivotally connected to the lower ends of a pair of short 20 crank arms 82 secured to a shaft 84 rotatably mounted in bearings near the lower end of a substantially vertical portion of the jack casting which connects its overhanging arm 16 to its lower arm 20. On the shaft 84 is secured a toothed 25 segment or gear member 86 engaging a second toothed segment or gear member 88 secured on a jack-operating lever arm 90 which is mounted to swing about a fixed shaft 92 in the jack casting. The arm 90 extends upwardly as indicated in Fig. 30 1 when the machine is idle, and by swinging this arm in a counterclockwise direction as viewed from the front of the machine the three-armed lever 72 is rocked also in a counterclockwise direction about the pins 74, thereby swinging the left-hand end of the floating lever 66 downwardly and thus through the springs 58 imparting upward movement yieldingly to the toe rest 10.

Swinging movement of the floating lever 66 is also utilized to cause the heel rest 12 to move 40 into engagement with the shoe after the toe rest has clamped the toe end of the shoe against the plate 8. The heel rest has thereon a pair of ears 94 connected by a pivot pin to the lower end of a link 96 which at its upper end is pivotally 45 connected by a pin 98 to a slide 100 mounted in a vertical T-shaped guideway formed in a guide 102 on the left-hand end of a horizontal slide 104, the slide 104 being mounted in a guideway provided in the upstanding portion of the jack 50 casting. The pin 98 actually passes through a slot 106 in the slide 100 and is fast in a plunger 108 slidably mounted in the upper end of the slide 100. The right-hand end of the plunger 108 has a plate 110 depending from it and provided on its right-hand face with ratchet teeth to cooperate with teeth formed on the left-hand face of the guide 102. The plunger 108 is urged toward the right by a spring plunger 112 in the slide 100. By pulling the heel rest 12 toward the 60 left the teeth on the plate 110 can be readily disengaged from the teeth on the guide 102 and the heel rest with the slide 100 may then be adjusted vertically to the most convenient position for engagement with any particular shoe.

A downwardly extending portion of the slide 100 has therein a screw 114 the head of which abuts against the lower end of the link 96. By turning this screw the heel rest may be swung about the pin 98 to accommodate it to the height-wise curvatures of the heel ends of different shoes. Spring-pressed plungers 116 located in the link 96 above and below the pivotal connection of the heel rest to the link provide means against which the heel rest may swing about 70 75

this pivotal connection in one direction or the other in the jacking of the shoe to adjust itself better to the curvature of the heel end of the shoe. A vertical screw 118 threaded in the lower 5 end of the guide 102 and a pin 120 in the upper end of the guide serve by contact with the slide 100 to prevent the slide from being moved vertically off its guideway.

The horizontal slide 104 for moving the heel 10 rest toward the shoe comprises a pair of long and narrow horizontal plates 122 spaced apart at their left-hand ends by a shank 124 on the guide 102, to which shank the plates are secured, the plates nearer their right-hand ends being 15 spaced apart by a distance piece 126 to which also they are secured. Near its right-hand end the slide 104 has positioned between its plates 122 a pair of comparatively short arms 128 which at their left-hand ends, with the parts positioned 20 as shown in the drawings, have forwardly and rearwardly extending pins 130 mounted in holes formed in the plates 122. The right-hand ends of these arms are connected together by a pin 132, and that pin 130 which extends forwardly 25 from the foremost arm has secured to it, at the front of the foremost plate 122, a crank arm 134 in which is mounted a spring-pressed plunger 136 (Fig. 2) arranged to enter one or the other of two holes 138 formed in the plate 122 at opposite sides of the pin 130, depending upon the 30 positions of the arms 128 as hereinafter explained. The right-hand end of the floating lever 66 is connected by a short link 140 to the left-hand end of a curved arm 142 of a bell-crank lever 144 mounted to turn on the shaft 84. The second arm 146 of this bell-crank lever, 35 which is arranged to lie substantially beneath the slide 104, extends upwardly and toward the right and is connected by a link 148, located between the two plates 122, to the pin 132 which connects the two short arms 128.

From the above description it will be understood that the toe rest and the heel rest are operatively connected respectively to the opposite 40 ends of the floating lever 66. When the floating lever is operated in the manner previously described by the three-armed lever 72 upon swinging movement of the arm 90, the left-hand end of the floating lever is first swung downwardly, the lever swinging about the connection 45 at its right-hand end with the link 140, and by this movement of the lever the toe rest is moved upwardly toward and into engagement with the shoe. When the toe rest has clamped the shoe firmly against the plate 8 and its upward movement is stopped by the shoe, continued movement of the arm 90 causes the floating lever to swing downwardly about the pivotal connection of its left-hand end with the link 54, and in this 50 movement its right-hand end swings the bell-crank lever 144 in a counterclockwise direction and thus imparts to the heel rest through the link 148 and the slide 104 a movement toward the left to cause it to abut against the heel end 55 of the shoe.

The arms 128 may be positioned to extend toward the right from their pivot pins 130, as shown in Figs. 2 and 3, or by swinging the crank-arm 134 through an arc of 180° may be positioned 60 to extend toward the left from the pins, the spring plunger 136 by entering the appropriate hole 138 maintaining them in either of these positions. Since the arms 128 are connected as described to the link 148, their swinging movement serves to move the slide 104 to the left 65

or the right through a distance equal to twice the length of the arms 128. A simple and convenient means is thus provided whereby the heel rest 12 may be quickly adjusted to operate more effectively on shoes of comparatively large sizes 5 or shoes of comparatively small sizes. The crank arm 134 carries a small knob secured to the spring plunger 136 whereby this plunger may be withdrawn from either of the holes 138.

In order to relieve the above-described heel-rest-operating mechanism of strain due to the heelward thrust of the shoe against the heel rest in the lasting operation, the machine herein shown, in general similarity to the machine shown in Letters Patent No. 1,993,117, is provided with 10 a pawl-and-ratchet device arranged to act on the slide 104. This device comprises a series of ratchet teeth 150 formed on a plate secured to the slide 104 and a pair of staggered pawls 152 arranged to engage the ratchet teeth to hold the 20 slide against movement toward the right after the heel rest has engaged the shoe. These pawls are fast on a pin 154 rotatable in the upwardly extending portion of the jack casting and they are urged toward the ratchet teeth by springs 156. 25 In order to disconnect the pawls from the ratchet teeth when the arm 90 is swung in the direction to release the shoe from the jack, a lever 158 is secured on the rear end of the pin 154. This lever carries a pin 160 which lies to the left of 30 upstanding fingers on the pawls and acts when the lever 158 is swung in a clockwise direction to disconnect the pawls from the ratchet teeth. For swinging the lever 158 by the movement of the arm 90 this arm carries a pin 162 arranged to engage a curved tail portion 164 of the lever.

As previously described, the toe rest 10 is forced 35 yieldingly against the shoe through springs 58 connecting the slide 50 to the left-hand end of the floating lever 66, and it will be evident that by 40 reason of their relation to the floating lever these springs are also yieldable in response to resistance of the shoe to the pressure of the heel rest against it. In order to afford increased insurance 45 that shoes of different sizes will be firmly clamped by the toe and heel rests, the machine herein shown is further provided with means whereby the toe and heel rests are thrust positively against the shoe after they have engaged it yieldingly. They are thereafter maintained in pressure-ap- 50 plying relation to the shoe by reason of the fact that by the operative movement of the arm 90 the double link 80, connected to the three-armed lever 72, and the short arms 82 on the shaft 84 are moved into substantially parallel relation to pro- 55 vide what is, in effect, a straightened toggle to maintain the toe and heel rests in operative positions until the arm 90 is swung reversely, i. e., to the right. Swinging movement of the arm 90 to its operative position is limited by a suitable stop 60 (not shown).

The means for rendering the springs 58 ineffective, so that the toe and heel rests will be forced 65 positively against the shoe, is mounted on the upper end of the link 54 which carries the slide 65 50 to which the toe rest is connected. This means acts at a suitable time to render the link 54 positive in its action on the slide 50, as far as downward movement is concerned, so that further 70 bodily downward movement of the floating lever 66 effected by the three-armed lever 72 will act positively both on the toe rest and on the heel rest. The slide 50 has teeth 166 formed along its right-hand face and the link 54 has a bracket 75 168 extending toward the right from its upper end,

in which bracket are slidingly mounted three pawls 170, one only of which is shown in the drawings. These pawls are arranged side by side and have teeth 172 on their left-hand ends. The 5 teeth on the three pawls are in staggered relation heightwise of the machine and are arranged to engage the teeth 166 on the slide 50 at a certain time. The bracket 168 has a substantially horizontal guideway for the pawls 170, and a cover 10 plate 174 fast on the bracket under the pawls supports them in the guideway. The bracket also has two coaxial bearings 176 for a sliding rod 178, the bearings being spaced apart to provide room between them for a pawl-controlling yoke 15 180 secured by screws on the sliding rod. A pair of springs 182 between the left-hand bearing 176 and the yoke 180 tend to force the yoke and the rod 178 toward the right, and a depending portion 184 of the yoke acts on upstanding portions 186 of the pawls to move the pawls also in that direction, the movement of the yoke being limited by contact with the right-hand bearing 176. Springs 188 located between the ends of pockets formed in the yoke 180 and in the pawls 20 170 tend to force the pawls toward the left to engage their teeth with the teeth 166.

Until after the toe rest and the heel rest, however, have actually engaged the shoe the yoke 180 remains in the position shown in Figs. 3 and 4 25 with the pawls 170 out of engagement with the teeth 166, so that the toe and heel rests may be forced yieldingly against the shoe. At a suitable time thereafter the rod 178 is moved toward the left to permit the pawls 170 to engage the teeth 166 so that the slide 50 becomes connected to the floating lever 66 for positive downward movement. For this purpose there is threaded in the right-hand end of the rod 178 a stud 190 having an enlarged head, and the double link 80 which 30 connects the three-armed lever 72 to the arms 82 on the shaft 84 has an ear 192 projecting upwardly from its left-hand end and provided with a pin having a roll 194 thereon. This roll lies in the same vertical plane, extending from right 35 to left, as the head of the stud 190, this plane being far enough to the rear for the parts to clear the upper of a long-legged boot, and during the final portion of the movement of the link 80 toward the left in the jacking of the shoe the roll 40 strikes against the head of the stud 190 and thus moves the yoke 180 toward the left to cause the pawls 170 to engage the teeth 166. The link 80 continues to move a little farther toward the left after the roll 194 has engaged the stud 190, as 45 the arm 90 nears the position in which it remains while the shoe is clamped in the jack, and in this movement the link depresses the floating lever 66 a little farther through the three-armed lever 72. Since the heel rest 12 is connected by positive 50 mechanism, including the bell-crank lever 144 and the links 140 and 148, to the right-hand end of the floating lever 66, and since the toe rest 10 is at this time positively coupled to the left-hand end of the floating lever as described, the further 55 depression of this lever serves to force the toe rest and the heel rest positively against the shoe, whatever may be the size of the shoe, thus insuring against displacement of the shoe in the jack in the lasting operation. As previously 60 stated, the toe rest and the heel rest are maintained in their operative positions by the straightening of the toggle device provided by the link 80 and the arms 82. The toe rest 10 is formed of rubber so that it may yield sufficiently 65 to avoid damage to the shoe or the jack mecha-

nism. The exact time in the jacking of the shoe when the toe rest and the heel rest are forced positively against it may be varied by adjusting the amount which the stud 190 is screwed into the rod 178, so as to vary the distance that the roll 194 has to travel before engaging the stud. 70

The above-described operating mechanism for the toe and heel rests is such as to permit them to engage and hold securely shoes of widely varying sizes and styles, the heel rest being adjustable in directions lengthwise of the shoe by the crank arm 134 and the toe rest being adjustable, if necessary, by the screw 34 in the manner previously explained. Portions of the operating mechanism for the toe and heel rests are displaced rearwardly of a vertical plane passing through these rests so as to permit the upper of a long-legged boot to hang freely down without being obstructed by any portion of this mechanism. 75

The left-hand end of the lower horizontal arm 20 of the jack casting has extending through it a vertical bore the axis of which is substantially in position to pass through the extreme toe end of the shoe clamped in the jack. A vertical pivot pin 196 extends upwardly into this bore from a socket member 198 which is supported by a pair of coaxial pins 200 in the upper end portion of a bifurcated link 202 the lower end portion of which straddles a part of the frame and is pivoted on a pin 204 in the frame (Fig. 1). The right-hand end of the lower horizontal arm of the jack casting carries a short pin 206 secured in a lug 208 depending therefrom, and a roll 210 is mounted on this pin. This roll rests on a flattened upper 80 face of a forwardly and rearwardly extending rod 212 the opposite ends of which are secured to portions of the bifurcated upper end of an upstanding link 214 similar to the link 202 and substantially parallel to the latter. The lower end 85 of the link 214 is bifurcated and straddles the top portion of an upstanding web 216 on the frame, and it is pivotally mounted on a pin 218 in the web. The jack casting may swing about the vertical pin 196 in a forward or rearward direction 90 in the lasting operation in response to pressure of one or the other of the wipers 5 on the shoe so that the wipers may bear evenly on the opposite sides of the shoe. The two parallel links 202 and 214 are of the same length and their lower 95 pivotal supports are at the same height. The links are tied together at their upper ends by means of a substantially horizontal rod 220 offset rearwardly from beneath the overhanging arm 16 of the jack casting. The rear end of the rod 212 extends through the right-hand end of the rod 220, and through the left-hand end of the latter extends the rear end of one of the pins 200 connecting the socket member 198 to the link 202. 100

Pivoted on the two pins 200 are the right-hand ends of a pair of substantially horizontal rods 222 extending to the left at the front and rear of the bearing through which the vertically movable trunk 7 extends, only one of these rods 105 being visible in the drawings. The left-hand ends of these rods (Fig. 1) are pivoted on pins which extend from a trunnion member 224 into portions of the bifurcated upper end of a link 226 similar to the links 202 and 214 and parallel to 110 them, the link 226 being pivoted at its lower end on a pin 228 secured in a lug 230 on the frame. A rod 232 extends toward the right and somewhat upwardly through the trunnion 224 and through vertical slots provided in the vertically movable 115

trunk 7 and its bearing. The rod 232 also extends toward the left and has at its left-hand end a hand wheel 234 for turning it. Collars 236 are pinned to the rod 232 at the opposite sides of the trunnion 224, and a coil spring 238 is located between the right-hand side of the trunnion and the corresponding collar 236 to provide frictional resistance against undesired rotation of the rod 232. The right-hand end of the rod 232 is threaded into a socket member 240 which is pivotally mounted on a pin 242 secured in the upper end of an upwardly extending arm 244 of a bell-crank lever 246 mounted on a pin 248 in the frame. A second arm 250 of this bell-crank lever extends downward and toward the left and has an upper flat face covered by a leather pad 252. When no shoe is clamped in the jack this pad is arranged to engage a flattened lower face of a pin 254 which is secured in the frame. The two links 202 and 214 on which the jack is supported, and also the third link 226, are somewhat inclined toward the right when there is no shoe in the jack, so that the weight of the jack acts through the rod 232 to maintain the arm 250 of the bell-crank lever 246 in contact with the pin 254. In this condition the jack is spaced to the right from the position which it occupies in the lasting operation a distance which may be varied by turning the rod 232 through its hand wheel 234. Since the rod 232 is prevented from moving lengthwise relatively to the trunnion 224 on the link 226 and is threaded in the socket member 240, the position of which is determined by the bell-crank lever 246 and the pin 254, the link 226 is necessarily swung by the turning of the rod and causes equal swinging movements of the jack-supporting links 202 and 214.

The jack is moved a predetermined distance toward the wipers simultaneously with the clamping of the shoe by the toe and heel rests. For this purpose the three-armed lever 72 has a downwardly extending arm 256 the lower end of which is connected by a link 258 to the lower end of a depending arm 260 of a bell-crank lever 262 which is mounted on a pin 264 located in the jack casting in substantially the same forward and rearward vertical plane as the pin 196 about which the jack swings. The second arm 266 of this bell-crank lever extends toward the left and is connected by a ball joint to the upper end of a link 268. The lower end of this link is connected, also by a ball joint, to the previously mentioned bell-crank lever 246, the point of connection between this link and the bell-crank lever 246 being located substantially between the two arms of the latter. Accordingly, as the three-armed lever 72 is operated to clamp a shoe by means of the toe rest and the heel rest as previously described, it acts at the same time to swing the bell-crank lever 262 in a counterclockwise direction and thereby to impart a similar movement to the bell-crank lever 246. It will be evident that this movement of the bell-crank lever 246 causes the link 226 to be swung toward the left, and since this link is connected to the links 202 and 214, these links are swung in the same direction and carry the jack with them. The jack is maintained in the position to which it is thus carried by the links through the same means which maintains the toe and heel rests in operative positions, i. e., by the toggle arrangement provided by the link 80 and the arms 82 connecting this link to the shaft 84.

Since the arm 90 is always moved to the same

position in jacking a shoe of whatever size, the amount of movement of the jack toward the wipers will always be the same. This may, for example, be about two inches, so as to provide sufficient clearance between the wipers and the plate 8 to permit the shoe to be readily positioned against the plate without interference by the wipers. It will be evident, however, that the exact position to which the jack is moved may be varied as desired by means of the hand wheel 234 which by its rotation varies the initial or starting position of the jack.

The links 202 and 214 supporting the jack may be, for example, about seven inches in length, and they swing but a short distance in moving the jack toward the wipers as above described. The links, moreover, are initially inclined but little from the vertical, and in moving the jack they swing substantially to vertical positions. In this operation, therefore, the upward movement of the upper ends of the links is so slight as to impart but a very small heightwise movement to the jack and shoe. Since the links are parallel, no tipping of the shoe takes place in the movement of the jack.

In order to provide further support for the jack an additional link 270, of the same length as the links 202 and 214 and parallel thereto, is pivoted on the frame between these links but is offset rearwardly therefrom. The link 270 has secured in spaced ears at its upper end a pin on which is pivoted an arm 272 extending toward the right and pivoted at its right-hand end on the rear end of the rod 212 to which the link 214 is connected as previously described. This insures that the link 270 will always remain parallel to the other jack-supporting links. The arm 272 has extending upward from it above the link 270 a pair of ears in which is secured a horizontal pin 274 (Fig. 2) which is substantially radial to the pin 196 on which the jack swings laterally, and on this pin 274 is mounted a roll 276 which bears against a track face 278 (Fig. 3) extending rearwardly and toward the left from the lower arm of the jack casting so that the roll and track face maintain their engagement during swinging movements of the jack about the pin 196.

The machine is further provided with a knee-operated jack release device 280 which the operator may use instead of the arm 90 to cause the jack to withdraw from the wipers and release the shoe. This device includes a depending rod 282 secured adjustably in a bifurcated yoke 284 which is pivoted on the ends of the rod 212. The yoke 284 has a face 286 so arranged that when the device 280 is swung toward the right to un-jack the shoe this face strikes against the lower end of a plunger 288 slidably mounted in the jack casting. On its upper end (Fig. 5) this plunger has a head arranged to strike against a finger 290 secured on the gear sector 86 and thus to turn the shaft 84 in a counterclockwise direction to break the toggle 80, 82. When this occurs the toe and heel rests are returned to their starting positions and the weight of the jack parts, assisted by a spring hereinafter referred to, causes the jack to be returned toward the right to its inoperative position. As the link 54 to which the toe rest is connected rises during the unjacking of the shoe and as the roll 194 which causes the pawls 170 to engage the teeth on the slide 50 moves toward the right, these pawls are moved out of engagement with the slide

by the action of the springs 182 on the yoke member 180.

In order to assist the operator in beginning to move the jack toward or away from the wipers 5 there is provided means which gives an impulse to the jack in the desired direction when the operator swings the arm 90 in the appropriate direction. This means comprises springs 292, 294 mounted loosely on the forward one of the 10 two previously mentioned rods 222 (Fig. 1), these springs bearing respectively at their outer ends against collars 296, 298 clamped on the rod. A lug 300 fixed on the bearing for the trunk 7 surrounds the rod 222 between the inner ends of 15 the springs, and the springs are spaced so far apart that when the jack is in its inoperative position the left-hand end of the right-hand spring 294 is spaced somewhat from the lug 300, while the right-hand end of the left-hand spring 20 292 abuts against the lug and is under compression. When the jack begins to move toward the wipers, therefore, the spring 292 expands and assists initially in such movement of the jack, and since the jack rises slightly as it moves in 25 this direction, this spring may conveniently be somewhat stronger than the spring 294. As the jack approaches its operative position the spring 292 moves out of engagement with the lug 300 and the spring 294 engages it and becomes somewhat compressed. Therefore, when the jack later 30 begins to move toward inoperative position the spring 294 expands to assist in such movement of the jack.

By reason of the arrangement of the gear sectors 86, 88 and the length of the arm 90, this arm 35 operates the jacking mechanism with considerable mechanical advantage, thus lightening the work of the operator. This arrangement, moreover, gives the desirable result that movement of 40 the jack toward the left and toward the right is effected by swinging movements of the arm 90 in those same directions.

Having described the invention, what I claim 45 as new and desire to secure by Letters Patent of the United States is:

1. In a machine for operating on shoes, a shoe-positioning device for engaging the bottom of a shoe, a toe rest and a heel rest for engaging the shoe respectively at the top of the forepart and 50 at the heel end to hold the shoe, and mechanism movable by the operator to force said toe rest and heel rest first yieldingly and then positively against the shoe after the shoe has been presented in contact with said shoe-positioning device.

2. In a machine for operating on shoes, a shoe-positioning device for engaging the bottom of a shoe, a toe rest and a heel rest for engaging the shoe respectively at the top of the forepart and 55 at the heel end to hold the shoe, a member common to said toe rest and heel rest and movable by the operator to force them against the shoe, and mechanism controlled by said member for operating said toe and heel rests first yieldingly and then positively.

3. In a machine for operating on shoes, a shoe-positioning device for engaging the bottom of a shoe, a toe rest and a heel rest for engaging the shoe respectively at the top of the forepart and 60 at the heel end to hold the shoe, a member common to said toe rest and heel rest and movable by the operator to force them against the shoe, and mechanism for operating said toe and heel rests by the movement of said member, said 65 mechanism comprising parts relatively movable

against yielding resistance upon engagement of the toe and heel rests with the shoe and also means for thereafter positively connecting said parts to force the toe and heel rests unyieldingly against the shoe.

4. In a machine for operating on shoes, a shoe-positioning device for engaging the bottom of a shoe, a toe rest and a heel rest for engaging the shoe respectively at the top of the forepart and at the heel end to hold the shoe, a member movable by the operator to force said toe and heel rests against the shoe, a floating lever operated by said member, connections between said floating lever and the toe and heel rests including a spring yieldable upon engagement of said toe and heel rests with the shoe, and means for substituting a positive connection for said spring in the continued movement of said member.

5. In a machine for operating on shoes, a shoe-positioning device for engaging the bottom of a shoe, a toe rest and a heel rest for engaging the shoe respectively at the top of the forepart and at the heel end to hold the shoe, a member movable by the operator to force said toe and heel rests against the shoe, a floating lever operated by said member, positive connections between one end of said floating lever and the heel rest, connections between the other end of said lever and the toe rest including a spring yieldable upon engagement of the toe and heel rests with the shoe, and a device for rendering the connections between the lever and the toe rest positive in the continued movement of said member.

6. In a machine for operating on shoes, a shoe-positioning device for engaging the bottom of a shoe, a toe rest and a heel rest for engaging the shoe respectively at the top of the forepart and at the heel end to hold the shoe, a member movable by the operator to force said toe and heel rests against the shoe, intermeshing gear members arranged to be operated by said first-named member, and connections between one of said gear members and the toe and heel rests for operating them.

7. In a machine for operating on shoes, a shoe-positioning device for engaging the bottom of a shoe, a toe rest and a heel rest for engaging the shoe respectively at the top of the forepart and at the heel end to hold the shoe, a member movable by the operator to force said toe and heel rests against the shoe, intermeshing gear members arranged to be operated by said first-named member, a crank arm operated by one of said gear members, a link connected to said crank arm, and connections between said link and the toe and heel rests for operating them, said crank arm and link being movable to positions in substantially parallel relation to each other for maintaining the toe and heel rests in shoe-holding positions.

8. In a machine for operating on shoes, a shoe-positioning device for engaging the bottom of a shoe, a toe rest and a heel rest for engaging the shoe respectively at the top of the forepart and at the heel end to hold the shoe, a floating lever connected to said toe and heel rests for moving them against the shoe, and mechanism including intermeshing gear members movable by the operator to operate said floating lever.

9. In a machine for operating on shoes, a shoe-positioning device for engaging the bottom of a shoe, a toe rest and a heel rest for engaging the shoe respectively at the top of the forepart and at the heel end to hold the shoe, a floating lever connected to said toe and heel rests for moving

them against the shoe, another lever connected to said floating lever for operating the latter, a link connected at one end to said other lever, a crank arm connected to the other end of said link, and a member movable by the operator to operate said crank arm.

10. In a machine for operating on shoes, a shoe-positioning device for engaging the bottom of a shoe positioned bottom upward, a toe rest and a heel rest for engaging the shoe respectively at the top of the forepart and at the heel end to hold the shoe, a floating lever, means for moving said floating lever in a downward direction, and connections between said floating lever and the toe and heel rests for raising the toe rest and for moving the heel rest toward the heel end of the shoe by the downward movement of the floating lever.

11. In a machine for operating on shoes, a shoe-positioning device for engaging the bottom of a shoe positioned bottom upward, a toe rest and a heel rest for engaging the shoe respectively at the top of the forepart and at the heel end to hold the shoe, a floating lever, means for moving said floating lever in a downward direction, a lever connected to said toe rest and movable to raise the toe rest by the downward movement of the floating lever, and lever-and-link connections between the floating lever and the heel rest for moving the heel rest also into engagement with the shoe by the downward movement of the floating lever.

12. In a machine for operating on shoes, a shoe-positioning device for engaging the bottom of a shoe, a toe rest and a heel rest for engaging the shoe respectively at the top of the forepart and at the heel end to hold the shoe, a member for moving said toe and heel rests against the shoe, and connections between said member and the toe and heel rests for operating them, the connections to the heel rest comprising an arm mounted to swing adjustably to different positions for effecting a preliminary adjustment of the heel rest lengthwise of a shoe.

13. In a machine for operating on shoes, a shoe-positioning device for engaging the bottom of a shoe, a toe rest and a heel rest for engaging the shoe respectively at the top of the forepart and at the heel end to hold the shoe, a slide supporting said heel rest and movable in directions lengthwise of the shoe, a link for operating said slide to force the heel rest against the shoe, and a device pivotally connected to said link and mounted on said slide for turning movement to effect a preliminary adjustment of the slide relatively to the link.

14. In a machine for operating on shoes, the combination with means for operating on a shoe, of a shoe support, parallel links on which said shoe support is mounted for movements in directions lengthwise of a shoe thereon, said parallel links being arranged to be swung in a direction to carry the shoe support away from said operating means by the weight of the support thereon and being movable reversely to carry the support with each shoe toward the operating means, mechanism for holding the support positively in position for the shoe to be operated upon and for thereafter releasing it from such positive control to permit movement thereof away from the operating means by gravity, and stop mechanism for limiting movement of the support away from the operating means.

15. In a machine for operating on shoes, the combination with means for operating on a shoe,

of a shoe support, parallel links on which said shoe support is mounted for movements in directions lengthwise of a shoe thereon, said parallel links being arranged to be swung in a direction to carry the shoe support away from said operating means by the weight of the support thereon and being movable reversely to carry the support with each shoe toward the operating means, mechanism for holding the support positively in position for the shoe to be operated upon and for thereafter releasing it from such positive control to permit movement thereof away from the operating means by gravity, a lever connected to the support, and a relatively fixed member for engaging said lever to limit movement of the support away from the operating means.

16. In a machine for operating on shoes, the combination with means for operating on a shoe, of a shoe support, parallel links on which said shoe support is mounted for movements in directions lengthwise of a shoe thereon, said parallel links being arranged to be swung in a direction to carry the shoe support away from said operating means by the weight of the support thereon and being movable reversely to carry the support with each shoe toward the operating means, and a spring arranged to assist in initiating the movement of the support away from the operating means.

17. In a machine for operating on shoes, the combination with means for operating on a shoe, of a shoe support, parallel links on which said shoe support is mounted for movements in directions lengthwise of a shoe thereon, said parallel links being arranged to be swung in a direction to carry the shoe support away from said operating means by the weight of the support thereon, means for moving the support toward the operating means, and a spring arranged to assist in initiating such movement of the support toward the operating means.

18. In a machine for operating on shoes, the combination with means for operating on a shoe, of a shoe support provided with means for clamping a shoe thereon, a member movable to operate said clamping means, parallel links on which said shoe support is mounted for movements toward and from said operating means, and mechanism arranged to be operated by said member to impart to the shoe support a movement toward the operating means accompanied by the swinging of said parallel links.

19. In a machine for operating on shoes, the combination with means for operating on a shoe, of a shoe support provided with means for clamping a shoe thereon, a member movable to operate said clamping means, parallel links on which said shoe support is mounted for movements toward and from said operating means, a lever mounted independently of the shoe support and arranged to be operated by said member, and means for imparting to the shoe support a movement toward the operating means by the movement of said lever.

20. In a machine for operating on shoes, the combination with means for operating on a shoe, of a shoe support provided with means for clamping a shoe thereon, a member movable to operate said clamping means, parallel links on which said shoe support is mounted for movements toward and from said operating means, a lever mounted independently of the shoe support, connections between said member and lever for swinging the lever by the movement of said member, and connections between the lever and the parallel links

for moving the shoe support toward the operating means by the swinging of the lever.

21. In a machine for operating on shoes, the combination with means for operating on a shoe, of a shoe support mounted for movements toward and from said operating means and provided with means for clamping a shoe thereon, a member on the shoe support movable by the operator to operate said clamping means, a lever mounted independently of the shoe support and arranged to be swung by the movement of said member, and means for imparting to the shoe support a movement toward said operating means by the swinging of said lever.

15 22. In a machine for operating on shoes, the combination with means for operating on a shoe, of a shoe support mounted for movements toward and from said operating means and provided with means for clamping a shoe thereon, a member on 20 the shoe support movable by the operator to operate said clamping means, a lever mounted independently of the shoe support but connected thereto to swing as the shoe support moves toward or from said operating means, a stop arranged to engage said lever to limit movement of 25 the shoe support away from the operating means, and connections between said member and lever for operating the lever to move the shoe support toward the operating means by the movement of 30 said member.

23. In a machine for operating on shoes, the combination with means for operating on a shoe, of a shoe support mounted for movements toward and from said operating means and provided with means for clamping a shoe thereon, a lever mounted on the shoe support to swing in 35 directions toward and from the operating means, and mechanism for operating said clamping means to clamp a shoe and for moving the shoe support toward said operating means by the 40 swinging of said lever in that direction.

24. In a machine for operating on boots and shoes, the combination with means for operating on the toe end of a boot or shoe, of a work support provided with upper and lower arms connected together and extending toward said operating means, said work support having means for supporting a long-legged boot bottom upward and being mounted to swing laterally about an

axis located in the vicinity of the toe end of the boot, and a portion of said lower arm being offset laterally to clear the depending leg of the boot.

25. In a machine for operating on boots and shoes, the combination with means for operating on the toe end of a boot or shoe, of a work support provided with upper and lower arms connected together and extending toward said operating means, a device supported on said upper arm for engaging the bottom of the forepart of a 10 long-legged boot presented bottom upward, a toe rest supported on said lower arm for clamping the forepart of the boot against said device, and a heel rest for engaging the heel-end face of the boot, a portion of said lower arm being offset laterally to clear the depending leg of the boot.

26. In a machine for operating on shoes, a heel rest for engaging the heel end of a shoe, a depending link supporting said heel rest and mounted at its upper end to swing about an axis 20 extending laterally of the shoe, and means for adjusting the link about said axis.

27. In a machine for operating on shoes, a heel rest for engaging the heel end of a shoe, and spring means against the resistance of which said heel rest is movable in one direction or the other about an axis extending laterally of the shoe in response to pressure of the shoe against it.

28. In a machine for operating on shoes, a heel rest for engaging the heel end of a shoe, a support for said heel rest adjustably movable in directions heightwise of the shoe, and spring-controlled retaining means movable to release said support and permit its adjustment and arranged to maintain it in different adjusted positions.

29. In a machine for operating on shoes, a heel rest for engaging the heel end of a shoe, a slide supporting said heel rest and adjustably movable in directions heightwise of the shoe, a depending link supported at its upper end by said slide to swing about an axis extending laterally of the shoe, means for adjusting the link about said axis, and means supporting the heel rest on said link for movement against yielding resistance about an axis extending laterally of the shoe for better accommodation to the shape or position of the shoe.

WILLIAM THOMAS BUCKINGHAM ROBERTS.
